UNITED STATES PATENT OFFICE.

ROBERT G. FLEMING, OF NEWARK, NEW JERSEY, ASSIGNOR TO THE SMOKADOR MANUFACTURING COMPANY INC., OF BLOOMFIELD, NEW JERSEY.

COMBINATION CIGARETTE HOLDER AND SMOKING TUBE.

Application filed July 11, 1923. Serial No. 650,797.

To all whom it may concern:

Be it known that I, ROBERT G. FLEMING, citizen of the United States, residing at Newark, in the county of Essex and State of New Jersey, have invented certain new and useful Improvements in Combination Cigarette Holders and Smoking Tubes, of which the following is a specification.

This invention relates to certain new and useful improvements in combination cigarette holder and smoking tube, and the primary object thereof is to provide a device which enables a cigarette to be firmly supported at a distance from the smoker during smoking thereof.

A further object of the invention is to provide a device of this type which may be easily and quickly attached at any desired point to flat surfaces of various kinds, for example table tops, beds, automobile windshields, ash trays, or other places, and which may be easily and quickly removed without damaging or marring the surface to which the device is applied.

The invention still further aims to provide a device of this kind wherein the cigarette is held so as to cause the ashes to be caught and thus be prevented from dropping onto the floor, and which enables the cigarette stub to be easily and quickly ejected from the holder.

Another object of the invention is to provide an attachment in the nature of a combined windshield and ash collector for special use of the invention in a vertical position in an automobile.

In the drawings:—

Figure 1, is a side elevation of the invention applied to a table or the like;

Figure 2, is a front elevation of the clip;

Figure 3, is a section on line 3—3 of Figure 2;

Figure 4, is a section on line 4—4 of Figure 2;

Figure 5, is a vertical sectional view of the invention applied to an automobile windshield;

Figure 6, is a section on line 6—6 of Figure 5, and

Figure 7, is a fragmentary perspective view of the invention applied to an ash stand of the self-righting type.

In proceeding in accordance with the present invention, a support is employed which

embodies a substantially U-shaped spring 55 clip having side arms 1 formed with complementary intermediate curved parts or jaws 2 and arc-shaped outer ends, the latter being divergently related and conjointly affording a flared mouth for the clip. The base of the clip is perforated to receive and interlock with the head 4 of a rubber vacuum cup 5. The cup 5 is formed to engage against any flat surface with which an air-tight seal can be effected. The cup is depressed to expel 65 air between it and the surface so that the pressure of the surrounding air acting against the outer face of the cup, will hold the latter in position.

The cigarette holder embodies a sleeve 6, 70 the bore of the outer end of which is flared to afford a socket to receive the cigarette and is provided with a curved or rolled edge 7 which acts to strengthen and reinforce the holder and to also afford means for engagement with the spring jaws 8 formed on and by slitting the lower end of a foraminous ash retaining sleeve 9. The ash retaining sleeve is particularly designed for automobile use, Figure 5, by way of example, depicting the 80 clip attached horizontally to a glass wind-shield.

The holder sleeve 6 is formed with a pair of spaced peripheral flanges 10, the space in length being slightly greater than the 85 width of the jaws 2 so as to allow the sleeve to be placed in the mouth of the clip and then moved downwardly to occupy the space between the jaws and with the flanges 10 engaging the side edges of the arms 1 of the 90 clip. The cigarette holder is thus firmly supported against axial movement or movement transversely of the clip.

The sleeve 6 has a counterbored inner end 11 in which and the remainder of the bore 95 of the sleeve, a tube 12 is positioned. The tube 12 has a perforated head 13 which is disposed in the socket of the holder sleeve 6 and which provides an ejector means for expelling burnt cigarette stubs. The counterbore 11 receives therein a coil spring 14, which surrounds the tube 12 and which at one end abuts the inner wall resultant from the forming of the counterbore 11. The outer end of the coil spring abuts a coupling 15 which is threaded over the outer end of the tube 12 and which is slidable within the counterbore 11. A section of rubber

tubing 16 of desired length is connected to the coupling 15 and is equipped with a mouthpiece 17.

In Figure 7, the invention is illustrated in connection with the self-righting pedestal ash tray cigarette holder of my copending application for patent filed July 11, 1923, Serial No. 650796 and wherein the holder sleeve 6 is gripped by and between the two jaws 18 and 19 and with its flanges 10, engaging the opposed side edges of the jaws. In this use of the invention, the lighted end of the cigarette is held over the ash tray or receptacle 20, equally true of the showing of the invention in Figure 1, in which latter the clip is supported on a table and in overlying relation to an ash tray 21 of the table supported type. In both of these examples of use, ashes from the cigarette are caught by the tray, while in the instance of Figure 5 of the drawings, the ventilated ash-sleeve 9 collects and retains the ashes.

The invention is of special utility for smokers assuming a reclining or horizontal position, eliminating the danger of igniting bed or furniture coverings, since in the instances of use exemplified in Figures 1 and 7 the lighted cigarette is held at a safe and predetermined distance from the bed or lounge.

The spring clip is formed so as to retain the cigarette holder at such distance above the surface of a table or other support to permit the insertion of an ash tray below the cigarette so as to catch the ashes.

In use of the invention, as instanced in Figure 5 of the drawings, in connection with a vehicle, the sleeve 9 functions as a

windshield, preventing ashes from being blown from the cigarette, and trapping same as they drop.

However, it is to be expressly understood that the examples of use herein noted are to be considered as such and not as exhaustive enumeration of all uses to which the device may be put.

It is also to be noted that the invention is equally susceptible of use in retaining the cigarette in either vertical or horizontal position.

What is claimed is:—

1. In a combined cigarette holder and smoking tube, a receiver, a cigarette holder, gripping means formed to removably engage said holder, spaced flanges on the holder formed to engage opposite sides of the gripping means so as to prevent longitudinal movement of the holder in the gripping means and to retain the holder with the lighted end of the cigarette in a predetermined position overlying the receiver, and a tube having one end connected to the holder and its opposite end provided with a mouth piece.

2. In a combined cigarette holder and smoking tube, a receiver, a cigarette holder, means formed to removably support the holder, means to prevent axial movement of the holder in the supporting means and to retain the holder with the lighted end of the cigarette in a predetermined position overlying the receiver, and a tube having one end connected to the holder and its opposite end provided with a mouth piece.

In testimony whereof I affix my signature.
ROBERT G. FLEMING.
